(57) **CLAIM**

The ornamental design for a dryer vent termination grate, as shown and described.

DESCRIPTION

FIG. 1 is an environmental, side perspective view of the dryer vent termination grate shown in FIG. 1, wherein the dryer vent termination grate is shown installed in a dryer vent;

FIG. 2 is an environmental, side perspective view of the dryer vent termination grate shown in FIG. 1, wherein the dryer vent termination grate is shown exploded from the dryer vent;

FIG. 3 is a bottom perspective view of the dryer vent termination grate shown in FIG. 1;

FIG. 4 is a front elevational view of the dryer vent termination grate shown in FIG. 1;

FIG. 5 is a rear elevational view of the dryer vent termination grate shown in FIG. 1;

FIG. 6 is a top elevational view of the dryer vent termination grate shown in FIG. 1;

FIG. 7 is a bottom elevational view of the dryer vent termination grate shown in FIG. 1;

FIG. 8 is a right side elevational view of the dryer vent termination grate shown in FIG. 1; and,

FIG. 9 is a left side elevational view of the dryer vent termination grate shown in FIG. 1.

The dash-dot-dot lines illustrate the boundary of the claimed design.

The exterior geometric shape of the depicted vertical bars of the dryer vent termination grate is disclaimed, and can have a round and/or circular cross-sectional shape as shown, or a shape with a plurality of sides, e.g., a triangle, a quadrilateral, a 5-sided shape, a 6-sided shape, or any other suitable number of sides).

Surface shading or stippling is included in the drawings to show the character and contour of the surfaces of the three dimensional aspects of the dryer vent termination grate or to show contrasting surfaces unlimited by colors.

(Continued)

The features illustrated in evenly-spaced dashed lines are included for illustrative purposes only to depict the environment of the dryer vent termination grate and form no part of the claimed design.
